UNITED STATES PATENT OFFICE.

CHARLES C. CURTISS, OF GRAND RAPIDS, MICHIGAN.

DESIGN FOR A DRAWER-SECTION.

46,247.

Specification for Design.

Patented Aug. 11, 1914.

Application filed April 27, 1914. Serial No. 834,870. Term of patent 14 years.

To all whom it may concern:

Be it known that I, CHARLES C. CURTISS, a citizen of the United States, and a resident of the city of Grand Rapids, in the county of Kent and State of Michigan, have invented a new, original, and ornamental Design for Drawer-Sections, of which the following is a specification, reference being had to the accompanying drawing, forming a part thereof, and which fully discloses the essential features and characteristics of the design, such that others may fully understand the same.

The figure is a perspective view of a section showing my new design.

My design comprises in its essential features a frame 1 which is adapted to receive a plurality of drawers therein with the fronts thereof filling the open front side of the frame, said frame being fashioned at the top and bottom so as to receive a similar frame thereabove and rest on a similar frame below in the well known manner and method used in building up sectional furniture. The drawers are positioned in the frame in a plurality of vertical series which lie side by side though slightly spaced apart by vertical partitions 2. Each drawer front is comprised of a pair of spaced apart verti-

cal side members 3 located at the sides of the drawer which are connected at their lower ends by a horizontal member 4 located at the bottom of the drawer, said members 3 and 4 providing a frame open at the top to receive a glass panel adapted to close the open space between the members 3. Each drawer is provided with a knob or drawer pull 5 attached at the middle point of the member 4.

With a plurality of drawers of the design described located one above the other to form a vertical series of drawers, and with a plurality of said vertical series positioned side by side within the frame as shown, there is provided an article of original and attractive appearance, pleasing to the eye of the observer.

I claim:

The ornamental design for a drawer section substantially as shown and described.

In testimony whereof I have hereunto affixed my signature in the presence of two witnesses.

CHARLES C. CURTISS.

Witnesses:

GEO. H. DAKIN,
FRANK E. LIVERANCE, Jr.
